DRIVING MECHANISM WITH PILOT CONTROL

Frederick B. Small, Waterloo, N. Y., assignor to
Seneca Falls Machine Company, Seneca Falls,
N. Y., a corporation of Massachusetts

Application September 8, 1949, Serial No. 114,615

3 Claims. (Cl. 74—388)

1 This invention relates to a driving mechanism in which a relatively small pilot or control device renders a continuously rotated power member operative or inoperative with respect to a member to be driven.

As shown in the drawings, a power shaft is continuously rotated and a pilot or control device selectively couples an output shaft to said power shaft for rotation thereby.

In the preferred construction, the power shaft continuously rotates in a single direction but the output shaft may be selectively rotated in either direction.

It is the general object of my invention to improve the construction of the coupling devices by which the power shaft is selectively connected to the output shaft.

A further object is to provide a construction in which the coupling devices are fully enclosed and effectively protected.

My invention further relates to arrangements and combinations of parts which will be herein-after described and more particularly pointed out in the appended claims.

A preferred form of the invention is shown in the drawings, in which

Fig. 1 is a plan view of my improved driving mechanism, partly in section;

Fig. 2 is a front elevation, looking in the direction of the arrow 2 in Fig. 1 and partially broken away to show interior parts;

Fig. 3 is a diagrammatic view showing an application of the invention to a contour lathe;

Figs. 4 and 5 are detail sectional elevations, taken substantially along the lines 4—4 and 5—5 in Fig. 1 and with certain parts omitted; and

Fig. 6 is a plan view of the associated driving drums and certain coacting parts.

Referring to the drawings, my improved driving mechanism is mounted in an outer casing C having partitions P and P' (Fig. 1). The mechanism includes a power shaft 10 mounted in fixed bearings in the front plate of the casing C and in the partition P. The shaft 10 is continuously rotated from any convenient source of power, such as a motor M (Fig. 3), and a pinion 12 is fixed to its inner end.

Hollow cylinders 15 and 16 are mounted on ball or roller bearings 17 and 18, and the cylinder 15 is provided with a gear 20 engaged by the driving pinion 12. The cylinder 16 is similarly mounted and is provided with a gear 21 of the same size as the gear 20 and meshing therewith.

A perforated inner drum 25 is mounted on a

2 shaft 26 preferably supported in a roller bearing 27 fixed in the partition P and itself supporting the ball bearings 17 previously described.

A gear 30 is loosely mounted on the front end 5 of the shaft 26 and may be adjustably secured thereto by a clamping screw 31 extending through a slot 32 in an arm 33 fixed on the shaft 26. The gear 30 is engaged by a gear 35 (Fig. 2) mounted on a pilot shaft 40 which may be selectively rotated intermittently in either direction by suitable control mechanism. One such mechanism is shown in Fig. 3 and will be hereinafter described.

A driven drum 50 (Fig. 1) is mounted adjacent 15 the perforated drum 25 but slightly spaced axially therefrom. The drum 50 is mounted on a shaft 51 rotatably supported on a roller bearing 52 fixed in the casing partition P', and a transmitting gear 54 is secured to the rear or outer end of 20 the shaft 51. The gear 54 continuously engages a gear 55 on the inner end of an output shaft 60, rotatably mounted in a fixed bearing 61.

A spiral band 65 (Fig. 6) encircles the associated drums 25 and 50, and the narrow end 65a of 25 the band is secured to the drum 25, while the wider outer end 65b is secured to the drum 50. On its outer surface, the band 65 is preferably provided with a friction surface 67 (Fig. 1) of sheet cork or some similar and equivalent material.

The construction of the parts enclosed by the cylindrical casing 16 is identical with the parts associated with the casing 15 and above described, except that the spiral band 70 is oppositely wound. The drum 25a in the casing 16 is mounted on a shaft 72 having a gear 73 adjustably secured thereto by an arm 74, and the gear 73 engages the pilot gear 35. The driven drum 50a (Fig. 6) is mounted on a shaft 75 supporting a gear 76 which engages the previously identified gear 55 on the output shaft 60.

The spiral bands 65 and 70 are so wound and tensioned that they normally contact the drums 25 and 50 or the drums 25a and 50a, and with 45 their outer surfaces or cork facings just slightly clearing the inner faces of the continuously rotating cylinders 15 and 16.

In the operation of my improved driving mechanism, the output shaft 60 is normally stationary and the pilot shaft 40 is also normally stationary but is subject to greater or less angular movement in a selected direction in accordance with the indications of a control or pilot device associated therewith.

If the shaft pilot 40 is slightly rotated anti-clockwise as viewed in Fig. 2, the gear 30 and drum 25 will be correspondingly shifted clockwise, thus unwinding and expanding the band 65 (Fig. 6) and causing the band to be engaged by the cylinder 15 (Fig. 1) which is continuously rotated clockwise.

The band 65 and associated driven drum 50 will then be rotated clockwise by the rotating cylinder 15 until the drum 50 has been turned an amount corresponding to the original displacement of the drum 25. Such rotation of the drum 50 will contract the band 65 and return it to its original position in which it clears the rotating cylinder 15.

Obviously, such shifting or adjustment of the driven drum 50 will cause corresponding but opposite movement of the output shaft 60 through the connecting gears 54 and 55, and will thus give the output shaft 60 an anti-clockwise adjustment corresponding in direction and extent to the original anti-clockwise displacement of the pilot shaft 40.

During such adjustment, the drum 25a and 50a will be correspondingly but idly rotated in a direction to more tightly contract the band 70, so that no driving relation will be established.

If the pilot shaft 40 is displaced reversely or clockwise, the band 70 will be expanded and will become operative, while the band 65 will remain contracted. The output shaft 60 will then be adjusted clockwise rather than anti-clockwise.

Provision is thus made for shifting the output shaft 60 in either direction in exact correspondence with the selected movement of the pilot shaft 40 but without requiring the pilot shaft to provide power for such shifting of the output shaft. The power is provided by the power shaft 10 through one or the other of the rotated cylinders 15 and 16.

In Fig. 3, I have shown an application of the invention as controlling the transverse position of a lathe tool T with respect to a rotated piece of work W, as in a contour lathe. The tool T is mounted on a cross slide 80 slideable crosswise on a carriage 81 which is moved longitudinally of the work on guideways 82 and 83.

A pattern plate N is mounted in fixed position and coacts with a detector or follower 85 pivoted at 86 on the cross slide 80 and having an insulated index arm 87 connected to a line wire L.

The free end of the arm 87 makes selective contacts with terminals 90 and 91 which are connected to a relatively small control motor M' through wires 92 and 93. The motor M' is also connected to a second line wire L' and is of the reversible type which will be rotated clockwise or anti-clockwise according as one or the other of the contacts or terminals 90 or 91 is engaged by the arm 87 under control of the pattern plate N.

The motor M' is connected through reduction gearing G to the pilot shaft 40 which is rotatably mounted in the front of the casing C. The output shaft 60 is shown as provided with a pinion 95 engaging a rack 96 mounted on the carriage 80.

The operation of this illustrative mechanism may be briefly described as follows:

As the carriage 80 is moved longitudinally along its guideways, the detector or follower 85 follows the contour of the fixed pattern plate N. As the contour changes, the arm 87 swings to the right or to the left to engage one or the other of the contacts 90 or 91. This causes the motor M' to selectively rotate the pilot shaft 40 either

clockwise or anti-clockwise. This movement of the pilot shaft 40 then causes the power shaft 10 to rotate the output shaft 60 and rack pinion 95 through the driving mechanism in the casing C as above described. The tool T is thus moved toward or away from the work W under the control of the pattern plate N, detector 85, motor M' and pilot shaft 40.

It will be understood that the application of the invention as shown in Fig. 3 is illustrative only, and that the invention is well adapted for more general application.

The construction herein described has the substantial advantage that the drums and friction bands are enclosed by the cylinders 15 and 16 and are thus fully protected from dirt and injury.

Having thus described my invention and the advantages thereof, I do not wish to be limited to the details herein disclosed, otherwise than as set forth in the claims, but what I claim is:

1. A driving mechanism comprising a continuously rotated power shaft, an output shaft, a cylinder continuously rotated by said power shaft, a band enclosed by said cylinder but normally free therefrom, an operative connection from one end of said band to said output shaft, a pilot device, and an operative connection from said pilot device to the other end of said band, said pilot device being effective to expand said band to engage said cylinder by movement of said device, and said cylinder being effective to turn said output shaft until movement of said control device ceases and until said band is contracted by further turning movement of said cylinder.

2. A driving mechanism comprising a continuously rotated power shaft, an output shaft, a pair of cylinders continuously rotated by said power shaft but in opposite directions, a band enclosed by each cylinder but normally free therefrom, an operative connection from one end of each band to said output shaft, a pilot device, and an operative connection from said pilot device to the other end of each band, said pilot device being effective to expand either one of said bands in its cylinder by movement of said device in a selected direction, and the associated cylinder being effective through said selected band to turn said output shaft in a coordinated direction until movement of said control device ceases and until said band is contracted by further turning movement of said cylinder.

3. The combination in a driving mechanism as set forth in claim 2, in which said control device comprises a normally stationary control shaft, a reversible motor connected to turn said shaft by power in either direction, and selective means to energize said motor.
